(57) **CLAIM**

The ornamental design for a chest harness, as shown and described.

DESCRIPTION

FIG. 1 is a front view of a chest harness showing my new design;

FIG. 2 is an upper edge view of the present invention;

FIG. 3 is a lower edge view of the present invention; and, FIG. 4 is a side edge view of the present invention.

The broken line showing of environmental subject matter is for illustrative purposes only and forms no part of the claimed design. The broken lines shown on the surface of the chest harness are understood to represent stitching.
